FABRIC GUIDING DEVICE AND METHOD

George Kahn, Lawrence, and Leo Schwartz,
New York, N. Y.

Application July 26, 1945, Serial No. 607,149

16 Claims. (Cl. 112—152)

1

The present invention is directed to guiding devices for fabric during the course of sewing operations, and more particularly to a device which renders it feasible to sew or hem both edges of a piece of fabric at the same time. In the production of various articles on a commercial scale, it becomes necessary to sew or hem both edges of a relatively long strip of fabric. To accomplish this, it has become customary to pass the fabric through suitable folders and then through the sewing machine in order to hem one of the edges thereof. Then it was necessary to fold or roll the sewed fabric and then pass the same again through the sewing machine in a similar manner in order to hem the opposite edge thereof.

Attempts have been made to conduct the operation as a single unit by passing the fabric through the sewing machine to sew both edges at the same time. However, such attempts have failed because of various difficulties which render it impossible to accomplish the same. The present invention seeks to overcome such difficulties and disadvantages and to provide a method of sewing fabric and a device for accomplishing the purpose, whereby a single passage of the fabric through the machine will sew both edges thereof.

It is also among the objects of the present invention to provide a device which is simple in character and which may be attached to a standard sewing machine, said device acting as a guide and accomplishing the desired results.

It is further among the objects of the present invention to provide a device of the character described, wherein the guide member has elements which are adjustable to provide the desired direction of passage of the fabric and to maintain, adjust and alter tensions thereon in order to insure proper operation thereof.

In the accompanying drawing constituting a part hereof, and in which like reference characters indicate like parts;

Fig. 1 is a front elevational view of a sewing machine with the device of the present invention in place for operation; and

Fig. 2 is a vertical cross-sectional view of the device shown in Fig. 1 and illustrating particularly the relative arrangement of guide and the needles of the sewing machine.

There is provided the usual sewing machine having a base or bed 1 and a sewing head 2 having a pair of needles 3 and 4 therein. None of the mechanism of the sewing machine is illustrated or described and said machine operates as usual.

At the front of the base 1 are a pair of ver-

tical angle members 5 and 6 secured to member 1 below bed 1 of the machine. Members 5 and 6 constitute a frame on which the guiding device is mounted. It includes a rod 8 at the lower end of angles 5 and 6 placed in a position which is at a small or acute angle to the horizontal. One end of rod 8 passes through opening 9 in angle 6 and is held in position by nuts 10. A slot 11 in angle 5 is provided at the lower end thereof. The free end of rod 8 passes through slot 11 and a nut 12 is threaded on the end of said rod whereby the same may be clamped in any one of a plurality of positions, as shown in Fig. 1. Just above rod 8 is a pair of horizontal parallel bars 13 secured between end members 14 and having threaded rods 15 passing through openings in angles 5 and 6. Nuts 16 serve as means for clamping the same to the frame.

Above the pivoted bars are a series of four horizontal fixed bars 17, the ends of which pass through openings in angles 5 and 6 and the rods are held therein by clamping nuts. A guide plate 18 fits over rods 17 in vertical position approximately centrally of said rods. Movable guide plates 19 and 20 are mounted on either side of plate 18 and a thread and nut arrangement 21 and 22 is provided for clamping plates 19 and 20 in adjusted positions.

Above the fixed bars there is mounted a fixed rod 23 between angles 5 and 6. A pair of swinging bars 24 in a horizontal position is mounted on end members 25, the latter being loosely mounted on rod 23. Thereby the frame just formed is adapted to swing. Two such swinging frames are provided, each being on one side of the center of rod 23.

At the top of angles 5 and 6 is secured a rod 26 having mounted thereon a pair of wheels 27 which are provided with convex faces, bosses 28 having set screws therein providing means for fixing the position of said wheels on rod 26.

The frame and its associated guide parts are so mounted that the center line thereof is approximately between needles 3 and 4. Folders or hemming attachments 29 are secured to base 1 in alignment and between wheels 27 and needles 3 and 4 as shown in Fig. 1.

Fabric 30 in relatively great length and on rolls or otherwise packed is threaded between bars 13 and is passed upwardly, being threaded through bars 17 and then through swinging frame 24. It passes upwardly over wheel 27 at the right of Fig. 1, the convex surface or wheel starting a fold in the inner edge of the fabric. The latter passes through folder 29 as shown at 31 where the fold is completed, and it passes

as shown at 32 over the bed of the machine under needle 4 where the hem is stitched.

It then passes downwardly at 33 at the back of the machine and around rod 8 as shown at 34, then passing upwardly successively through pivoted rods 13, fixed rods 17, swinging rods 24, wheel 27 and folder 29 as indicated at 35. It then passes under needle 3 as shown at 36 so that the other side of the fabric is hemmed.

The inclination of rod 8 from the horizontal gives a sufficient angle to the fabric as it passes around the same to cause it to travel parallel to fabric 30 and a proper positioning thereof in the sewing machine is obtained. Depending upon the width of the cloth will depend the angle of rod 8. It may be adjusted to various angles based upon the type of fabric, its width and other factors. Pivoted bars 13 may be held in a position where practically no tension is exerted on either of the plies of fabric passing through the same. If desired, bars 13 may be twisted into one position or the opposite one so as to exert tension on the other of said plies.

Guide plates 19 and 20 may be adjusted laterally on bars 17 so that they prevent the fabric from moving from side to side and thus insure a proper movement of the fabric into the needles. Wheels 27 need not necessarily be rotatable and their position may be other than shown at the top of the guide frame. They may in some cases be entirely omitted.

Although the invention has been described setting forth a single embodiment thereof, it will be apparent to those skilled in the art that various changes in the details and construction may be made within the spirit of the invention. The guide frame need not be made of angles but may be made of other structural shapes and the several bars and rods may be held therein differently than shown. Some of the bars may be omitted or others may be added to give decreased or increased effects. Various materials of construction as are well known may be employed. These and other changes may be made without departing from the spirit of the invention, the scope of which is to be broadly construed and not to be limited except by the character of the claims appended hereto.

We claim.

1. A fabric guide for sewing machines comprising a frame attached to the bed of a sewing machine forwardly of and below the same, a rod secured in said frame and adapted for adjustment in a plurality of positions at an acute angle to the horizontal to guide fabric into said machine, said frame including a pair of depending lateral members, one end of said rod being mounted on one of said members for pivotal movement, the other end of said rod being mounted in the other member, and means for clamping said other end in a plurality of positions in a vertical plane.

2. A fabric guide for sewing machines comprising a frame attached to the bed of a sewing machine forwardly of and below the same, a rod secured in said frame and adapted for adjustment in a plurality of positions at an acute angle to the horizontal to guide fabric into said machine, said frame including a pair of depending lateral members, one end of said rod being pivoted in one member of said frame, a slot in the other member of said frame, the other end of said rod passing through said slot and means for clamping the same in adjusted positions in said slot.

3. A fabric guide for sewing machines comprising a frame attached to the bed of a sewing machine forwardly of and below the same, a rod secured in said frame and adapted for adjustment in a plurality of positions at an acute angle to the horizontal to guide fabric into said machine, said frame including a pair of depending lateral members, one end of said rod being pivoted in one member of said frame, a slot in the other member of said frame, the other end of said rod passing through said slot and means for clamping the same in adjusted positions in said slot, and a plurality of parallel horizontal bars in said frame above said rod through which fabric may be threaded.

4. A fabric guide for sewing machines comprising a frame attached to the bed of a sewing machine forwardly of and below the same, a rod secured in said frame and adapted for adjustment in a plurality of positions at an acute angle to the horizontal to guide fabric into said machine, one end of said rod being pivoted in said frame, a slot in said frame, the other end of said rod passing through said slot and means for clamping the same in adjusted positions in said slot, a pair of parallel horizontal bars joined together at their ends, means for pivoting said bars in said frame, and means for holding said bars in adjusted pivoted position to provide tension on fabric threaded through said bars.

5. A fabric guide for sewing machines comprising a frame attached to the bed of a sewing machine, a rod secured in said frame and adapted for adjustment in a plurality of positions at an acute angle to the horizontal to guide fabric into said machine, one end of said rod being pivoted in said frame, a slot in said frame, the other end of said rod passing through said slot and means for clamping the same in adjusted positions in said slot, and a plurality of parallel horizontal bars in said frame above said rod through which fabric may be threaded, a plurality of wheels having convex faces mounted in said frame above said bars, said fabric being adapted to pass over the same to initiate a fold therein.

6. A fabric guide for sewing machines comprising a frame attached to the bed of a sewing machine, a rod secured in said frame and adapted for adjustment in a plurality of positions at an acute angle to the horizontal to guide fabric into said machine, one end of said rod being pivoted in said frame, a slot in said frame, the other end of said rod passing through said slot and means for clamping the same in adjusted positions in said slot, and a plurality of parallel horizontal bars in said frame above said rod through which fabric may be threaded, a plurality of wheels having convex faces mounted in said frame above said bars, said fabric being adapted to pass over the same to initiate a fold therein, a plurality of folders above said wheels and in alignment therewith for completing said fold.

7. A fabric guide for sewing machines comprising a frame attached to the bed of a sewing machine, a rod secured in said frame and adapted for adjustment in a plurality of positions at an acute angle to the horizontal to guide fabric into said machine, one end of said rod being pivoted in said frame, a slot in said frame, the other end of said rod passing through said slot and means for clamping the same in adjusted positions in said slot, a pair of parallel horizontal bars joined together at their ends, means for pivoting said bars in said frame, and means for holding said bars in adjusted pivoted position to provide ten-

sion on fabric threaded through said bars, a plurality of parallel fixed horizontal bars above said pivoted bars having laterally adjustable guide plates mounted thereon.

8. A fabric guide for sewing machines comprising a frame attached to the bed of a sewing machine, a rod secured in said frame and adapted for adjustment in a plurality of positions at an acute angle to the horizontal to guide fabric into said machine, one end of said rod being pivoted in said frame, a slot in said frame, the other end of said rod passing through said slot and means for clamping the same in adjusted positions in said slot, a pair of parallel horizontal bars joined together at their ends, means for pivoting said bars in said frame, and means for holding said bars in adjusted pivoted position to provide tension on fabric threaded through said bars, a plurality of parallel fixed horizontal bars above said pivoted bars having laterally adjustable guide plates mounted thereon, and a plurality of parallel horizontal bars mounted to swing freely above said fixed bars.

9. A fabric guide for sewing machines comprising a frame attached to the bed of a sewing machine forwardly of and below the same, a rod secured in said frame and adapted for adjustment in a plurality of positions at an acute angle to the horizontal to guide fabric into said machine, said frame including a pair of vertical, spaced angle members between which said rod is held, one end of said rod being mounted on one of said members for pivotal movement, the other end of said rod being mounted in the other member, and means for clamping said other end in a plurality of positions in a vertical plane.

10. A fabric guide for sewing machines comprising a frame attached to the bed of a sewing machine, a rod secured in said frame and adapted for adjustment in a plurality of positions at an acute angle to the horizontal to guide fabric into said machine, one end of said rod being pivoted in said frame, a slot in said frame, the other end of said rod passing through said slot and means for clamping the same in adjusted positions in said slot, a pair of parallel horizontal bars joined together at their ends, means for pivoting said bars in said frame, and means for holding said bars in adjusted pivoted position to provide tension on fabric threaded through said bars, a plurality of parallel fixed horizontal bars above said pivoted bars having laterally adjustable guide plates mounted thereon, and a plurality of parallel horizontal bars mounted to swing freely above said fixed bars.

11. A method of guiding fabric through a two-needle sewing machine to hem both edges thereof in a single operation which comprises guiding one edge of said fabric to one of the needles to sew said edge, looping the fabric from the rear of the machine to the front thereof, and passing the same over a guide to properly direct the same to the second needle to sew the other edge thereof.

12. A fabric guide for multiple needle sewing machines comprising a frame attached to the bed of a sewing machine forwardly of and below the same, a plurality of substantially horizontal cross members in said frame, a lateral guide on said members for threading fabric to be sewed upwardly through said members at one side thereof, means for angularly guiding said fabric to the lower part of the other side thereof, and an additional lateral guide at said other side to guide said fabric in a path lateral to said first path.

13. A fabric guide for multiple needle sewing machines comprising a frame attached to the bed of a sewing machine forwardly of and below the same, a plurality of substantially horizontal cross members in said frame, a lateral guide on said members for threading fabric to be sewed upwardly through said members at one side thereof, means for angularly guiding said fabric to the lower part of the other side thereof, and an additional lateral guide at said other side to guide said fabric in a path lateral to said first path, and guides adjacent to said needles for guiding at least two portions of said fabric simultaneously to said needles.

14. A fabric guide for multiple needle sewing machines comprising a frame attached to the bed of a sewing machine forwardly of and below the same, a plurality of substantially horizontal cross members in said frame, a lateral guide on said members for threading fabric to be sewed upwardly through said members at one side thereof means for angularly guiding said fabric to the lower part of the other side thereof, and an additional lateral guide at said other side to guide said fabric in a path lateral to said first path, and an inclined rod at the bottom of said frame over which said fabric is adapted to pass to said other side of said frame.

15. A fabric guide for multiple needle sewing machines comprising a frame attached to the bed of a sewing machine forwardly of and below the same, a plurality of substantially horizontal cross members in said frame, a lateral guide on said members for threading fabric to be sewed upwardly through said members at one side thereof means for angularly guiding said fabric to the lower part of the other side thereof, and an additional lateral guide at said other side to guide said fabric in a path lateral to said first path, some of said members being pivoted.

16. A fabric guide for multiple needle sewing machines comprising a frame attached to the bed of a sewing machine forwardly of and below the same, a plurality of substantially horizontal cross members in said frame, a lateral guide on said members for threading fabric to be sewed upwardly through said members at one side thereof means for angularly guiding said fabric to the lower part of the other side thereof, and an additional lateral guide at said other side to guide said fabric in a path lateral to said first path, and convexly surfaced wheels rotatably mounted on a horizontal axis at the upper part of said frame each of said convexly surfaced wheels lying under and being adapted to contact edges of said fabric to initiate folds therein.
